UNITED STATES PATENT OFFICE.

ERWIN D. McMILLEN, OF OMAHA, NEBRASKA.

FILE-CLEANING IMPLEMENT.

1,242,710.

Specification of Letters Patent.

Patented Oct. 9, 1917.

Application filed December 28, 1915. Serial No. 69,113.

To all whom it may concern:

Be it known that I, ERWIN D. McMILLEN, a subject of the King of Great Britain, residing at Omaha, Nebraska, have invented 5 certain new and useful Improvements in File-Cleaning Implements, of which the following is a specification.

This invention has relation to certain new and useful improvements in file cleaning implements, and has for its primary object, the provision of a device of this character which may be readily adjusted for cleaning various forms of files.

The invention has for another object, the 15 provision of adjustable blades having file cleaning teeth and means for supporting said blades in adjusted position.

The invention has for a further object, the provision of a file cleaning implement 20 of this character which will be of such construction that the blades may be readily adjusted with respect to one another and retained in adjusted position during use of the device.

25 A further object of the invention resides in the provision of a file cleaning implement of the above-stated character which will also include a brush adjustable in the blade carrying case and positioned at one end of 30 the blades.

The invention has for a still further object the provision of an implement of this character including blades having graduated teeth upon their working edges, and 35 means for separating the blades and retaining them in proper spaced relation for movement through the grooves of a file or the like to clean the same.

With the above and other objects in view, 40 the invention resides in the novel construction, combination, and arrangement of parts as hereinafter set forth in the specification, pointed out in the claims, and shown in the drawings, in which—

45 Figure 1 is a longitudinal section through the complete device;

Fig. 2 is a side elevation;

Fig. 3 is an enlarged elevation of one of the blades removed;

50 Fig. 4 is a sectional view through the same on the plane of line 4—4 of Fig. 3;

Fig. 5 is a transverse section on the plane of line 5—5 of Fig. 1;

55 Fig. 6 is a transverse section on the plane of line 6—6 of Fig. 1;

Fig. 7 is an enlarged fragmentary section of the parts shown in Fig. 5;

Fig. 8 is a detail view of one of the blade spacers.

Referring more particularly to the drawings in which similar reference characters designate corresponding parts throughout the several views, 1 designates a case which is preferably of elongated form and has transverse blade supporting rods 2 mounted 60 in its lower portion, the spaced file cleaning blades 3 being positioned upon said rods 2. The forward ends of the blades 3 are provided with outwardly inclined lower edges 4 and the entire lower edges 4 of said blades 3 are provided with the graduated teeth 5, the larger teeth being at the forward ends 65 of the blades 3 and terminating a short distance from the forward points 6 of said blades 3. The teeth at the rear ends of the 70 blades 3 are very small and resemble fine saw teeth. The lower edges of the blades 3 are beveled on one side, preferably the left side, as shown in Fig. 4, while the upper edges of said blades 3 are beveled upon both 75 sides, as shown clearly in Fig. 7 and designated by the numeral 7, the purpose of 80 which will presently appear.

It will be understood that the bottom of the case 1 is open and the lower edges of the 85 blades 3 project from the same. It will also be seen by referring to the drawing that a brush 8 is in the rear end of the case 1, directly back of the blades 3, the bristles of the brush projecting about the same distance as the lower edges of the blades 3. The brush 8 is mounted upon the side supporting pins 9 which project through the 90 rearwardly inclined elongated guide slots 10 in the sides of the case 1 and may be 95 readily adjusted by means of the adjusting screw 11 projecting through the rear end of the case 1 and having threaded engagement with the top of body 12 of the brush 8, said adjusting screw 11 being provided with a 100 suitable head 13 upon its outer end. It will be understood that the bristles of the brush 8 may be composed of fine steel wires or of any other suitable material.

The supporting rods 2 extend through the 105 forward and rearward portions of the blades 3 and in the upper edges of the blades 3 rearwardly of the forward rod 2 I have provided the recesses 14 having curved bottom walls and vertical front walls to pro- 110

vide the shoulders 15. I have also provided the blades 3 with the reversed slots 16 in their upper edges and forwardly of the rear rod 2, the slots 16 having curved lower walls 5 and rear walls to provide the shoulders 17 in front of the rear rods 2. Above the blades 3 and above the recesses 14 and 16 I have provided the forward and rear spacer carrying shafts 18. Upon the shafts 18 I have mounted the blade spacers 19 having the radial arms 20 with beveled side projections 21 to separate the blades 3 as the shafts 18 are rotated to bring the proper arms 20 to position between said blades 3 and thereby 10 retain the same in proper spaced relation. Each spacer 19 is preferably provided with three arms 20 differing in thickness and the spacers are slidable on and rotatable with each shaft 19 with their corresponding arms 20 parallel. It will also be seen that each spacer 19 has flanged sections 22 between the arms 20 which engage between the shoulders 15 and 17 to prevent the blades 3 from moving too near the center of the rods 2 under 15 influence of the tension springs 23 upon the opposite ends of said rods 2. It will also be seen that, while the arms 20 are riding in the recesses 14 and 16 or above the blades 3, they will not serve to separate the blades 3, but, as the arms 20 move to position between the shoulders 15 and the shoulder 17 they 20 will force the blades 3 to separate without danger of causing said blades 3 to bind upon the rods 2. The tension springs 24 mounted 25 upon the opposite ends of the shafts 18 exert an inward pressure upon the spacers 19 and serve to limit outward movement of the spacers 19 and automatically return said spacers to normal position upon the shafts 18 as the arms 20 are moved from between the shoulders 15 and the shoulders 17 of said 30 blades 3. The shafts 18 are also each provided with a suitable head 25 upon one end, exteriorly of the case 1, by means of which 35 said shafts 18 may be readily rotated.

From the foregoing, it will be readily apparent that by rotation of the shafts 18, the blades 3 may be readily forced apart or permitted to move toward one another under 40 influence of the springs 23 and thereby properly adjust the blades 3 with respect to one another to permit said blades to ride in the grooves of a file, the graduated teeth 5 and the bristles of the brush 8 removing all foreign matter from said grooves and thoroughly cleaning the file without injury to the same. It will also be seen that this instrument may be employed for cleaning various forms of files.

60 While the preferred embodiments of the invention have been shown and described, it will be understood that minor changes in the details of construction, and arrangement of parts may be resorted to within the scope 65 of the appended claims without departing

from the spirit of the invention or sacrificing any of the advantages of the same.

What is claimed is:

1. A file cleaning implement comprising a plurality of blades having their lower edges 70 serrated and curved upwardly at one end, a case for said blades, and operable means for varying the space between said blades within said case.

2. A file cleaning implement comprising 75 a plurality of blades having graduated teeth formed on one edge, means for supporting said blades, and means for adjusting said blades with respect to one another.

3. A file cleaning implement comprising 80 a plurality of blades having teeth formed on one edge, a brush at one end of said blades, a case for said blades and said brush, and means for adjusting said blades with respect to one another.

4. A file cleaning implement comprising a plurality of blades having teeth formed on one edge, a brush at one end of said blades, a case for said blades and said brush, and means for adjusting said brush.

5. A file cleaning implement comprising 85 a case, blades mounted in said case and having projecting edges, teeth formed on said projecting edges, means for separating said blades, means acting against the last-mentioned means to resiliently force said blades toward one another, and means for resiliently retaining the spacing means in normal position.

6. A file cleaning implement comprising 90 a case, blades mounted in said case and having projecting edges, graduated teeth formed on said projecting edges, a brush within said case at one end of said blades and adjacent the small teeth, means for adjusting said brush within said case, and means for guiding said brush.

7. A file cleaning implement comprising 95 a plurality of blades having recesses in their upper edges to form shoulders, a case 100 for said blades, means within said case for engagement with said shoulders to separate said blades, said means including spacing members having thin and thick radial arms, means for resiliently retaining said blades 115 in normal position, and means for resiliently retaining the spacing members in normal position.

8. A file cleaning implement comprising 120 a case, a plurality of blades positioned longitudinally in said case, transverse mounting means for said blades, said blades having projecting lower edges, rearwardly graduated teeth formed upon said edges, the forward end of said edges being beveled 125 upwardly, and means for adjusting said blades transversely of said case.

9. A file cleaning implement comprising 130 a case, a plurality of blades positioned longitudinally in said case, transverse mounting

means for said blades, said blades having projecting lower edges, rearwardly graduated teeth formed upon said edges, the forward end of said edges being beveled upwardly, means for adjusting said blades transversely of said case, and a brush within said case rearwardly of said blades.

10. A file cleaning implement comprising a case, a plurality of blades positioned longitudinally in said case, transverse mounting means for said blades, said blades having projecting lower edges, rearwardly graduated teeth formed upon said edges, the forward end of said edges being beveled upwardly, and means for adjusting said blades transversely of said case, the lower edge of said case being beveled to correspond with the forward end of said blades.

11. A file cleaning implement comprising a case, a plurality of blades within said case, pairs of spacing arms of different thicknesses adapted to be moved between said blades to separate the latter, and means for supporting said spacing arms.

25 12. A file cleaning implement comprising a case, a plurality of blades positioned in said case, a plurality of rotatable spacing members including arms of different sizes to be rotated between said blades to vary 30 the distance between the same, and means for resiliently retaining the said blades in normal position.

13. A file cleaning implement comprising a case, a plurality of normally spaced blades positioned in said case, means for supporting said blades, means for increasing the distance between said blades, and means for resiliently forcing said blades toward one another.

40 14. A file cleaning implement comprising a case, a plurality of normally spaced blades positioned in said case, operable means for variably separating said blades, and resilient means normally tending to move and 45 hold said blades in a normal relative position.

15. A file cleaning implement comprising

a case, a plurality of blades supported in said case, supporting means for said blades, operable means for variably separating said blades, said last-mentioned means including arms adapted to be moved between said blades, and resilient members mounted upon the blade supporting means normally tending to move and hold said blades in a 55 normal relative position.

16. A file cleaning implement comprising a plurality of blades, means for supporting the blades and holding them in relative position, and operable means for variably 60 changing the position of the blades with respect to each other.

17. A file cleaning implement comprising a plurality of blades, means for supporting and holding them in relative position, operable means for simultaneously and variably 65 changing the position of the blades relative to each other.

18. A file cleaning implement comprising a blade member having teeth on one edge 70 thereof, said teeth graduating in size and varying in direction of pitch from one end of the blade to the other.

19. A file cleaning implement comprising a plurality of parallel blades having teeth 75 thereon graduating in size and varying in pitch from one end of the blade to the other.

20. A file cleaning implement comprising a plurality of parallel blades having teeth thereon graduating in size and varying in 80 pitch from one end of the blade to the other, and a brush at one end of the blades.

21. A file cleaning implement comprising a casing, a plurality of toothed blades secured in the casing, and a brush mounted 85 in the casing and disposed at one end of said blades.

In testimony whereof I affix my signature in presence of two witnesses.
